REMOVABLE PUMPING TANK FOR AUTOMATIC DEVELOPING MACHINES

Andre Victor Leon Clement Debrie, Paris, France

Application July 17, 1951, Serial No. 237,145

Claims priority, application France
August 3, 1950

2 Claims. (Cl. 222—155)

1

In rapid developing machines, wherein the film is circulated within tubes of small volume in which the liquid is renewed by being replaced as it is dragged along by the film, it has been proposed to employ a feed pump sucking up the liquid in a removable tank that must be disconnected from the pump when it is desired to replace the liquid. This pump also may suck up the liquid in a stationary tank which then must be filled again in situ. At any rate, the tank confined within the developing machine requires a series of manual operations in order to be exchanged or recharged, while the priming of the pump is endangered and the liquid remaining in the pump risks to be altered.

The present invention has for its object to provide a removable tank which may be slidably positioned in a rapid developing machine wherein the film is circulated for example in opened tubular coils, and in which there is fixedly arranged a pump whose actuating means project outwardly in such a way that, when the tank is placed into the developing machine, the part that controls the action of the pump comes in contact with, and is actuated by corresponding parts connected with the machine and driven by a motor, said tank being relatively small in width and further comprising a handle, means for observing the liquid level in the tank, means for rapidly leading the pump discharge into the tubular coil to be fed, air admitting means, and means whereby the tank can be guided into and maintained in its working position.

The invention will be more clearly understood by referring to the accompanying schematic drawings which show, by way of non-limiting example, an embodiment thereof and in which—

Fig. 1 is an elevational sectional view showing a tank according to the present invention, introduced into a portion of developing machine;

Fig. 2 is a part view, in transversal section, showing three tanks of the same type, introduced into the same portion of the developing machine;

Fig. 3 is a part view, in horizontal section, on an enlarged scale, showing means whereby the tanks of Figs. 1 and 2 can be guided into and maintained in their working positions; and

Fig. 4 is a longitudinal part section corresponding to Fig. 3.

In these drawings, denoted by 1 are walls of a tank, substantially rectangular in section, embodying the present invention and comprising a hollow handle 2, filling plug 3 and a discharge fitting 4 connected for example with the end por-

tion 5 of a flexible pipe feeding the developing machine.

Incorporated into one of the walls of this tank, for example into the lowermost wall of the latter 5 when it is in its working position, is a pump 6 actuated by oscillations of a lever 7 passing through and beyond the said wall.

In the example shown, the opposite lying wall is provided with a flanged gutter-like part 8 whose flanges 9 are slidably guided in grooves 11 of an inverted gutter-like part 12 secured to the underside of a horizontal partition 13 of the developing machine.

The tank is thus suspended in its working position and is maintained in this position by a locking system here constituted, for example, by a resilient blade 14 carried by 12 and protruding away from a face 15 of the developing machine.

This blade, conveniently incurved, is raised, 20 when the tank is inserted, by a snag 16 carried by 8 and which, when the tank 1 is in its working position, passes through an aperture 17 so as to render the tank rigid with the machine framework 13, this aperture 17 being managed in the lowermost bent portion of the blade spring 14.

By raising the end 18 of blade 14 it is possible to disengage the snag 16 from the aperture 17 and withdraw the tank 1 by causing 8 to slide in 12.

When the tank 1 is pushed into its working position, the lever 7 of pump 6 is actuated by a cam 19 carried by a shaft 21 journaled in supports 22, secured to the wall 15 of the developing machine, and is rotated by a motor (not shown) actuating a sheave 23 rigid with one end of shaft 21. There are as many cams 19 as there 30 are supports 12 provided each for receiving a tank 1. Each of the tanks 1 is provided, for example within its handle, with a transparent tube 24 that permits of observing, through apertures 25, the liquid level in the tank 1. The pump sucks up the liquid through a pipe 26 and discharges the same through a pipe 27 passing through 40 5 into 5.

Means carried by the tank 1, but not shown, 45 are provided for regulating, or even completely stopping, the pump discharge through 5. Such means may comprise, for example, a needle-valve interposed into the discharge pipe 27 and preceded by a return, through a conveniently loaded 50 valve, towards the tank 1, the pump being so adjusted as to have constantly a surplus discharge.

Means for admitting air into the tank 1 are also carried out in a manner known per se and not 55 shown.

2

The pipe 5 of each tank may be easily branched, by means of a known fitting (not shown), into the feed pipe leading to the treatment tube to be fed.

It will be seen that the replacement, on the machine, of an empty tank by a filled one is effected rapidly and without trial, the only manoeuvres, necessary for the withdrawal, consisting in raising 18 and pulling the tank backwards, at first slightly, so as to stop the pumping, since 7 is then no more actuated by the cam 19, and to separate the pipe 5 from the feed pieces receiving this pipe 5 on the machine. The empty tank may then be withdrawn completely.

The latter is replaced by a filled tank by causing its slide 8 to engage into the stationary slide 12, whereupon the filled tank is pushed ahead a distance such as to permit of connecting the pipe 5 with the machine.

The filled tank then can be pushed completely into its working position; the part 16 raises the blade 14 and, when 16 penetrates into 17, the tank is locked and its pump 6 is set in operation by the lever 1 being actuated by the corresponding cam 18.

Without substantially departing from the scope of the invention, modifications may be effected in the particular means, hereinabove described, for fixing the tanks in the machine, observing levels of the liquid in each tank, regulating the discharge of this liquid, rapidly connecting each tank with the machine, filling each tank, etc., the said particular means being set forth merely by way of non-limiting examples.

In lieu of the alternately operated pump, each tank may have a rotary pump actuated by an outstanding gearing in mesh with a corresponding gearing rotated by the shaft 21, without the employment of cams such as 19.

Finally, the tanks may be made of any suitable material such as stainless steel, plastic materials, or the like.

What is claimed is:

1. Liquid supply apparatus for developers and the like, comprising, in combination, a frame; drive means having a cam turnably mounted on said frame; a tank adapted to hold a liquid; pump means located in said tank for pumping liquid out of the same and including an elongated, movable operating member extending through a wall portion of said tank; support means on said frame and tank supporting said tank for movement to and from an operating position on said frame where said operating member of said pump means engages said cam of said drive means to be driven thereby to operate said pump means to move liquid out of said tank only when the latter is in said operating position

thereof, said support means being in the form of an elongated guide having opposite side channels and being mounted on said frame, and an elongated plate fixed to said tank and having opposite free side edge portions slidably located in said channels of said guide, respectively; a pin fixed to said tank and extending outwardly from a wall thereof; and an elongated springy arm fixed to said frame and being formed with an aperture in which said pin is located when said tank is in said operating position thereof.

2. Liquid supply apparatus for developers and the like, comprising, in combination, a frame; drive means having a cam turnably mounted on said frame; a tank adapted to hold a liquid; pump means located in said tank for pumping liquid out of the same and including an elongated, movable operating member extending through a wall portion of said tank; support means on said frame and tank supporting said tank for movement to and from an operating position on said frame where said operating member of said pump means engages said cam of said drive means to be driven thereby to operate said pump means to move liquid out of said tank only when the latter is in said operating position thereof, said support means being in the form of an elongated guide having opposite side channels and being mounted on said frame, and an elongated plate fixed to said tank and having opposite free side edge portions slidably located in said channels of said guide, respectively; a pin fixed to said tank and extending outwardly from a wall thereof; an elongated springy arm fixed to said frame and being formed with an aperture in which said pin is located when said tank is in said operating position thereof; hollow handle means forming part of said tank and communicating with the interior thereof, said handle means having a wall portion formed with an opening passing therethrough; and transparent means located in said handle means opposite said opening thereof to render the level of liquid in said tank visible from the exterior thereof.
